UNITED STATES PATENT OFFICE.

CHARLES W. DORRICOFF, OF PHILADELPHIA, PENNSYLVANIA, ASSIGNOR TO ELECTRELLE COMPANY, OF PHILADELPHIA, PENNSYLVANIA, A CORPORATION OF PENNSYLVANIA.

CONTROLLING MECHANISM FOR PHRASING-BARS.

1,170,617.

Specification of Letters Patent.

Patented Feb. 8, 1916.

Application filed July 3, 1912. Serial No. 707,524.

To all whom it may concern:

Be it known that I, CHARLES W. DORRICOFF, a citizen of the United States, residing at Philadelphia, in the county of Philadelphia and State of Pennsylvania, have invented new and useful Improvements in Controlling Mechanism for Phrasing-Bars, of which the following is a specification.

My invention relates to controlling mechanism for manipulating phrasing bars employed in musical instruments.

While my invention is for general use it is especially adapted for operating flexible and composite phrasing bars employed in upright and grand pianos, whether adapted for manual playing, automatic playing, or both hand and automatic playing.

More particularly stated I seek to control various portions or sections of a composite phrasing bar by aid of the improved levers of my invention in such manner as to give the operator a wider range of control over the phrasing bar, and to enable him to lock the various movable portions of the phrasing bar in predetermined fixed positions at will.

My invention also relates to the construction and operation of expression levers used for handling the phrasing bar, so as to improve the efficiency of such levers and parts immediately associated therewith.

My invention further relates to means for improving the efficiency of the various parts and connections more or less related to the expression mechanism for instruments.

Reference is made to the accompanying drawings forming a part of the specification, and in which like letters indicate like parts.

Figure 1 is a fragmentary elevation showing my invention as applied to an upright piano. Fig. 2 is a fragmentary vertical section through an upright piano, and shows the location of the phrasing levers, the phrasing bar, the magnet rail, and various other parts. Fig. 3 is a detail showing in elevation the phrasing levers as adjusted by and for varying the expression. Fig. 4 is a horizontal section showing the expression levers as folded back into normal or inactive position. Fig. 5 is a detail showing in section three of the rocking levers used for handling the phrasing bar, and also

showing parts associated with said rocking levers. Fig. 6 is a detail showing the construction of one of the brackets. Fig. 7 is a detail showing how all of the phrasing levers may as a unit be locked in any desired predetermined relative position. Fig. 8 is a section on the line 17—17 of Fig. 7 looking in the direction of the arrow. Fig. 9 is a detail showing in elevation an eccentric used for actuating the locking mechanism shown in Figs. 7 and 8. Fig. 10 is a fragmentary section through a grand piano equipped with my improved controlling mechanism, and also with my improved device for rendering the expression mechanism inactive in order that the piano may be played by hand. Fig. 11 is a section on the line 20—20 of Fig. 10, looking in the direction of the arrow.

The casing of an upright piano is shown at 22, and contains practically all of the other parts. Mounted within the casing are two screw bolts 23 which support a pair of supporting bars 24, the latter being mounted upon the screw bolts by aid of nuts 25 as will be understood from Fig. 2. The supporting bars 24 are provided with roughened surfaces 26, and engaging these surfaces are brackets 27 provided with mating roughened surfaces, and adjustably held in position by aid of bolts 28. Mounted upon the brackets 27 is a magnet bar 29. Supported upon this magnet bar are two brackets 30, and secured to these brackets is a stationary shaft 31.

Journalled upon shaft 31 are three bell crank levers 32, 33, and 34, and connected with these bell crank levers are three connecting rods 35, 36 and 37 which are, in this instance, made of tough, heavy wire. These rods are severally connected with expression levers 38, 39, 40, the form of which may be readily understood from Figs. 3 and 4. Each expression lever is provided at its forward end with clips 41, 42, 43, each clip consisting of a pair of outstanding parallel lips between which normally lies an extended foldable portion of the lever as will be explained hereinafter. Pivottally mounted upon the forward end of each of the levers 38, 39 and 40 are foldable sections 44, 45, 46, which carry finger pieces 47, 48, and 49, that extend out in front of the key-board the finger-pieces being made preferably of

hard rubber. Each section 44, 45, 46, is provided at its pivotal end with a curved portion 50 (see Fig. 3) integral with it, and adapted to serve the purpose of a cam for holding the lever in a definite depressed position when the sections are folded downward, as shown in Fig. 3. Each section 44, 45, 46 is pivotally connected to its corresponding lever 38, 39, 40, by aid of a bolt 51 carried by the lever, and extending loosely through the section encircling each bolt 51 is a spiral spring 52 which maintains a gentle pressure against the adjacent section, forcing it between the parallel lips or clips of the corresponding lever to hold the sections in locked position, but permitting lateral movement of the sections 44, 45, 46, to free them from locking engagement with their clips. The operator by grasping one of the finger-pieces 47, 48 or 49 and imparting a slight lateral and sidewise movement thereto, which takes it from between the parallel lips before referred to, may turn the corresponding section 44, 45, or 46 upon its pivot formed by its bolt 51, and by so doing may bring the corresponding cam-like portion 50 (see Fig. 3) into either of the positions shown. The levers 38, 39, 40 are pivotally journaled upon a bearing 53 as will be understood from Figs. 2 and 4 and swing upon their respective pivotal supports as centers. The levers extend through a block 54, which is provided with slots for this purpose, the several slots being fitted with felt linings 55. The block 54 is disposed upon the underside of the key bed 56. A block 57 having more or less resemblance to the block 54 is similarly provided with slots which are fitted with linings 58 of felt, through which the levers 38, 39, 40 extend. The block 57 is mounted rigidly upon a slide 59, the latter being fitted into a slide-way 60 carried by a plate 61 as will be understood from Fig. 9. The plate 61 is provided with a lug 62 integral with it and serving as a bearing. Extending through this bearing is a revoluble shaft 63 carrying an eccentric 64. The shaft 63 extends through another bearing 65, and is provided at its outer or free end with a handle 66. The operator by grasping the handle 66 and turning it causes the shaft 63 and eccentric 64 to turn, so that the eccentric is forced against the adjacent end of the block 57. As the levers 38, 39, 40 extend through this block, and through the block 54 which is fixed, as indicated in Figs. 8 and 9, the movement of the block 57 relatively to the block 54 locks the levers 37, 38, 39, 40 in such respective positions as they happen for the moment to occupy. As may readily be seen from the foregoing description, therefore, the expression levers 38, 39, 40 may not only be depressed by hand to any desired extent within reasonable limits, but they may be held individually in the

positions into which they are thus brought, and may also as a group be clamped in other respective positions. Each bracket 30 is provided with an upwardly extending arm 67 integral with it. Another bracket 68 is provided and is disposed slightly out of alignment with the arm 67. By aid of the arms 67 and the bracket 68 are mounted two rocking shafts 69, 70, in alignment with each other. Another rocking shaft 71, parallel with the shafts just mentioned, is journaled in the arms 67. Mounted rigidly upon the shaft 69 is an arm 72, and mounted similarly upon the shaft 70 is an arm 72^a. Springs 73 are connected with the arms 72, 72^a and extend therefrom, being connected by aid of holes 74 (see Fig. 5) with the front portions of the respective brackets. Mounted rigidly upon the shaft 69 is a curved arm 75. A similar arm 76 is mounted upon the shaft 70, and the shaft 71 carries a straight arm 77. The curvature of the arms 75, 76 is such as to bring their lower ends into substantially the same vertical plane as the lower end of the arm 77, as will be understood from Fig. 2. The arms 75 and 77 (see Fig. 5) are by aid of connecting wires 78, 79 connected respectively with the bell crank levers 32, 33, each wire being simply hooked into the lower end of the bell crank lever as indicated in this figure. Whenever a bell crank lever is rocked in a clockwise direction according to Fig. 5, the proper arm is rocked in the same direction.

Two flat bars 80, 81 are mounted upon the ends of the magnet rail 29, and at their upper ends support the outer ends of the shafts 70, 69. The power shaft 82 is supported by the lower ends of the bars 80, 81 being journaled therein. A number of arms 83, 84, 85, 86 and 87 are supported upon the shafts 70, 71 and 69. These are at their lower ends connected to various hammer supporting sections 88, 89, 90, 91 together forming a phrasing bar through the medium of which the hammers may be moved toward and from the piano strings.

The hammers of the piano are shown at 92. A stationary hammer rest, having generally the form of a lengthy bar, provided with a felted surface, is shown at 92^a, and when the phrasing bar is moved out of the way, the hammers may engage the stationary hammer rest directly. The strings are shown at 93, and the string plate at 94.

The brackets 30 (see Fig. 2) are provided with projecting portions 101^a, and extending through these are screw bolts 101^b which are fitted with nut locks 101^c. The screw bolts 101^b being adjusted and tightened by the aid of the nut locks, the swing of the arms 84, 85, 86, is limited to a predetermined angular position, and the phrasing bar is thus effectively provided with limiting stops for defining its travel toward the rear of the

strings. The loudness of the sounds of the piano is thus adjustable, for the reason that the position of the phrasing bar controls the length of travel of the hammers toward the strings and consequently the loudness of the sounds. While, therefore, the expression is controllable at the will of the operator by the adjustment he gives to different portions of the phrasing bar, the limit of loudness, attainable by such control, is itself adjustable by the means just described.

The operation of the mechanism shown in Figs. 1 to 9 inclusive, may be readily understood from the foregoing description. The operator may swing the handles 47, 48, 49, into either of several different positions and by aid of these handles the various levers 38, 39, 40 may be turned, in different angular positions relative to the general position of the piano as will be understood from Fig. 3. When the handles 47, 48, 49, are swung downwardly and backwardly to their extreme positions beneath the piano key bed as indicated in Fig. 4 all parts of the phrasing bar are brought into their extreme positions to the left according to Fig. 2, and the hammers 92 now engage the stationary hammer rest 92^a. The phrasing bar is now completely out of action, and the piano may be played manually after the manner of any other manually operated piano, the expression being controllable by the force with which the keys are struck. The levers 38, 39, 40, being thus in their lowermost positions, may be locked in such positions if desired or in any predetermined position in the manner hereinafter described.

By aid of the handle 66, I can turn the eccentric 64 and thus lock the various levers 40 38, 39 and 40, severally in any desired position and thus set the different sections of the phrasing bar to different positions of adjustment so that when the piano is being played automatically and without manual assistance, certain expression effects may be had depending upon the adjusted positions of the different sections of the phrasing bar. Also by reason of the cam extensions 50 on the inner end of each of the swinging or 45 foldable sections 44, 45 and 46, I can in a like manner set the corresponding phrasing bar sections to different positions of adjustment, this being accomplished by folding or moving the swinging sections 44, 45 and 46 or either of them backward to different positions as illustrated, for instance, in Fig. 3, which backward swinging movement of the sections causes the cam extensions 50 thereof to engage the under side of the key base 50 of the piano and thus depress the levers 38, 39 and 40 or either of them to different extents, the said cam portions 50 holding the levers so depressed and to an extent depending upon the extent to which the swinging 60 section is moved backward. When the

swinging or foldable sections 44, 45 and 46 are folded completely back so that they lie parallel with their respective levers 38, 39 and 40, the phrasing bar as a whole will be moved backward to its maximum position 70 and thus bring the piano hammers 92 against the hammer rest rail 92^a, which is the normal position of the hammers when the latter are adjusted for manual playing. When the foldable sections 44, 45 and 46 are in the 75 position last referred to, by reason of the fact that the cam portions 50 bears against the underside of the key bed of the piano with considerable pressure, the said foldable sections will be held firmly in this position 80 without requiring additional holding means but they may be readily drawn forward to the position shown in Fig. 2 and locked in rigid relation with the levers 38, 39 and 40 by slightly moving the sections in a lateral 85 direction to enable them to enter between the clips 41, 42 on the end of each lever 38, 39 and 40, these clips which overhang the upper and lower edges respectively of the foldable sections constitute interlocking 90 means between the levers and their sections to hold them in rigid relation by permitting relative disengagement upon moving the foldable sections laterally whereby they may be swung back to different adjusted positions 95 as described or completely folded back.

For purposes of grand pianos, I arrange the mechanism somewhat differently, the principles involved however being identical with those above set forth, and used in connection with the upright piano.

Referring more particularly to Figs. 10 and 11, the casing of the grand piano is shown at 101, the strings at 102, and the hammers at 103. The hammer rail 104 extends lengthwise of the piano. The keys may be of the usual pattern. The striker rods are shown at 105^a and are actuated by the player mechanism. The upper ends of the striker rods are engaged by the rear ends 105 of the keys. Extending lengthwise of the piano, and located beneath the keys is a rocking shaft 106, and mounted upon the latter are a number of leaf springs 107 equal to the number of keys. Each leaf spring 110 engages the underside of a key as will be understood from Fig. 10. The rocking shaft 106 carries a radially projecting arm 108 which extends through a slot 109 in the board 110, the latter being disposed below 115 the keys. A cam 110^a engages the arm 108, and is provided with a handle 111. By turning this handle the cam 110^a is turned, and the arm 108 causes the shaft 106 to rock. When the handle 111 is turned into one of its extreme positions, therefore, the leaf springs 107 are forced against the under sides of the keys 105, the outer or free ends of the keys being thus raised, and the inner 120 ends brought into operative relation to the 130

playing mechanism. When, however, the cam 110^a is turned into its opposite extreme position, the arm 108 causes the shaft 106 to rock in the reverse direction so that the leaf springs 107 are lowered, and the keys 105 are brought into normal position for hand playing. The springs 107, and rocking shaft 106 also perform another object. By maintaining the keys in engagement 10 with the striker rods of the mechanical player, lost motion between the keys and the striker rods is avoided. As a consequence the frequency with which the keys may be actuated without impairment of 15 their functions is greatly increased. For instance, a particular key 105 being pressed upon by its particular spring 107 is held with a gentle pressure upon the corresponding striker rod. If, now, under control of 20 the playing mechanism the striker rod moves quickly upward, say two or three strokes in rapid succession, upon each descent of the striker rod it is followed closely by the rear end of the key, so that there is 25 no lost motion and no loss of time due to any lagging action by the key in following the striker rod. This is of very great importance in instances where the music is to be played rapidly, or where a particular 30 note is repeated in rapid succession. In such instances, it is desirable that the lost motion above mentioned may be obviated entirely. Except for the springs 107 taking care of this matter as above explained, not only 35 would the undesirable lost motion be developed, but it would introduce the difficulties stated, and in addition thereto, would introduce false rattling sounds of a mechanical nature, and might even interfere 40 with the time relations of the notes of the music. The springs 107 should be very light and delicate however, for the reason that otherwise they would place additional work upon the movable keys. Mounted upon the 45 underside of the plate 110 is a bracket 112, and adjacent to this bracket are three shafts 113, 114, 115. For the purpose of rocking these shafts I provide three levers 116, 117, 118. Each of these levers is journaled in 50 the bracket 112 by aid of the pivot pin 119. Each lever at its rear end is connected by a link 120 with an arm 121, the latter being secured upon the adjacent shafts 113, 114 or 115. These shafts are provided respectively with arms 122, 123, 124 and secured to the latter are connecting wires 125, 126, 127. These wires are severally connected with levers 128, 129, 130, and these levers are connected with retracting springs 128^a. 55 The phrasing bar is made up of sections 131, 132, 133, 134, connected together substantially as above described with reference to Figs. 3 to 9 inclusive.

The operation of the mechanism shown in 60 Figs. 10 and 11, will be readily understood

from the foregoing description. The operator by moving the handle 111 into a suitable position, places the piano in condition for manual playing, or mechanical playing, as the case may be. Supposing that the 70 mechanism is to be played mechanically, the parts are brought into the position indicated in Fig. 10. The depression of the levers 116, 117, 118, is closely analogous to the depression of the levers 38, 39, 40 above 75 described with reference to the upright piano. The depression of these levers rocks the various shafts 113, 114, 115, and in doing this causes the connecting wires 125, 126, 127 to be lowered, thus pulling down the 80 sections 131, 132, 133, 134, and increasing the distance from the hammers 103 to the strings 102 with which they are associated. The end sections of the phrasing bar move in parallel planes as above described, and 85 the middle sections have considerable angular movement relatively to each other and to the end sections, so that the range of expression of the middle portion of the piano is very great notwithstanding the fact that 90 an unusual number of keys may be employed, as above described.

What I claim is:

1. In expression mechanism for musical instruments, a hammer-supporting phrasing-bar, separate manually operable levers each having an operative connection with a part of said bar, a laterally yieldable finger-piece section having a pivotal connection with the forward end of each lever, said pivotal 95 connection permitting lateral deflection of the free end of the said section when the parts are in alignment, and interlocking means between each lever and its finger-piece section to hold the parts in rigid relation, 100 said means requiring lateral deflection of the finger-piece section to bring the parts into and out of interlocking engagement.

2. The combination with a musical instrument embodying a key-board, hammers and strings, of expression mechanism for varying the stroke of the hammers, embodying a hammer rest-rail made in sections, manually operable expression levers having operative connections with said rest-rail sections, 110 and clamping means engaging opposite faces of said levers for holding the same in different adjusted positions.

3. The combination of a musical instrument provided with a casing and with hammers, mechanism for varying the stroke of said hammers, expression levers connected with said mechanism for actuating the same, said levers being provided with foldable portions having cam-like extensions for 120 engaging said casing and thus holding said levers individually in predetermined positions.

4. The combination with a musical instrument having a key-bed and hammers, of a 130

- hammer-supporting phrasing bar, manually operable levers having operative connections with said bar to alter the position of the hammers, said levers being pivotally supported beneath the key-bed, a swinging section pivotally connected to the forward end of each lever and adapted to be swung back under the key-bed, means for holding each lever and its section in rigid relation, and means carried by each section adjacent its pivoted end for engaging the underside of the key-bed and thereby depressing its lever when the section is swung back under the key-bed.
- 15 5. The combination with a musical instrument having a key-bed and hammers, of a hammer supporting phrasing bar, and manually operable levers having operative connections with said bar for moving the latter to alter the position of the hammers, said levers being pivotally supported beneath the key-bed, and each lever having a swinging section pivotally connected to the forward end thereof, each section being adapted to be swung back parallel with its lever and having a portion adjacent its pivoted end arranged to contact with the underside of the key-bed when the section is swung back to hold the parts in adjusted positions.
- 20 6. The combination with a musical instrument embodying a key-board, hammers, and strings, of expression mechanism for varying the stroke of the hammers embodying a hammer-rest rail, manually operable expression levers having operative connections with said rail, grooved ways in which said levers move, and means associated with said
- 25 levers for adjustably clamping the latter against movement in the ways whereby the levers may be held in different adjusted 40 positions.
7. The combination with a musical instrument embodying a key-board, hammers, and strings, of expression mechanism for varying the stroke of the hammers, embodying 45 a hammer rest rail, manually operable expression levers having operative connections with said rail, clamping means for simultaneously engaging opposite faces of all said levers for holding the latter in different 50 positions of adjustment, and means for actuating said clamping means.
8. In expression mechanism for musical instruments, a hammer-supporting phrasing bar, separate manually operable levers each 55 having an operative connection with a part of said bar and each lever having laterally projecting clips at its forward end, and a swinging finger-piece section pivotally connected to the forward end of each lever, each 60 section being arranged to take a position between the clips on the lever to which it is pivoted to hold the lever and section in rigid relation and adapted upon lateral movement thereof to be disengaged from between the 65 clips to enable the section to be swung back under the piano key-bed.

In testimony whereof I have hereunto set my hand in presence of two subscribing witnesses.

CHARLES W. DORRICOTT.
